UNITED STATES PATENT OFFICE.

CHARLES W. MCCOY, OF SPOKANE, WASHINGTON, ASSIGNOR TO REFRIGERATOR CAR EQUIPMENT CO., OF CHICAGO, ILLINOIS, A CORPORATION OF WASHINGTON.

TEMPERATURE-REGULATING DEVICE.

Application filed December 30, 1918. Serial No. 268,829.

To all whom it may concern:

Be it known that I, CHARLES W. McCoy, a citizen of the United States, residing at Spokane, in the county of Spokane and 5 State of Washington, have invented a certain new and useful Improvement in Temperature-Regulating Devices, of which the following is a specification.

This invention relates to temperature regulating devices and has for its object to provide a new and improved device of this description particularly adapted to be used in connection with temperature varying devices for moving compartments such as cars 15 or other vehicles including boats, or upon any moving device. The invention has among other objects to utilize the motion of the vehicle to assist in producing a circulation of air in the compartment the temperature of which is to be regulated. The invention is illustrated in the accompanying drawings wherein—

Figure 1 is a sectional view of a vehicle with one form of temperature regulating 25 device embodying the invention;

Figure 2 is an enlarged view of the device shown in Figure 1 with the top of the vehicle removed and with parts broken away;

Figure 3 is an enlarged view showing one 30 of the air moving devices in the vehicle;

Figure 4 is an enlarged view showing the driving device for the air moving device.

Like numerals refer to like parts throughout the several figures.

Referring now to the drawings I have shown a vehicle 1^a provided with a suitable temperature varying device adapted to act upon the air in the interior of the car so 40 as to vary its temperature to make it different from the temperature of the exterior atmosphere. This temperature varying device may be either a cooling or heating device depending upon the season of the year 45 in which it is used. For purposes of illustration I have shown a particular construction of temperature varying device, but it is of course evident that various other constructions may be used.

50 In the construction shown there are a plurality of receptacles 1, 2, 3 and 4, the receptacles 1 and 2 being located near one end of the vehicle and the receptacles 3 and 4 near the other end thereof.

55 Between the receptacles 1 and 2 I pro-

vide a series of valves 5 which open when pressure is applied to them on one side and which close when pressure is applied to them on the other side. Between the receptacles 3 and 4 I provide similar valves 6. 60 The valves 5 and 6 open in opposite directions. A pipe 7 connects receptacles 2 and 3, and a pipe 8 connects receptacles 1 and 4. When the receptacles and pipes contain liquid, the circulation of this liquid is produced by the movement of the vehicle. If, for example, the vehicle moves from side to side liquid will pass from tank 1 to tank 2, but cannot pass back because the valves 5 would close. This liquid will then pass 70 through pipe 7 and liquid will pass from receptacle 3 to receptacle 4 but cannot return because of valve 6. Liquid will then pass through pipe 8 back to receptacle 1 and thus a circulation will be secured. If it is 75 desired to cool the receptacle a cooling liquid will be circulated, such for example, as salted water. This liquid may be cooled before being inserted in the receptacles or may be cooled by ice or by melting ice in the 80 receptacles. If it is desired to heat the compartment a warm or heated liquid is used. In attempting to regulate the temperature of a compartment it is necessary to provide a proper circulation of the air. This circulation 85 of air is secured in part by variations in temperature but for many purposes the maintaining and securing of a circulation of air by this means is defective and unsatisfactory because the circulation is only produced when there is a variation in temperature between the different parts of the vehicle, and one of the objects which it is necessary and desirable to secure in many instances is a uniform temperature. It will 90 thus be seen that under such conditions if the air circulation is dependent upon variations in temperature, there must be produced a condition which is objectionable. In the present case this objectionable condition is obviated as I have provided means for producing a circulation of air independent of the variations in temperature.

95 In this construction I provide in the vehicle one or more air moving devices 10 located in the car at a suitable point or points so as to cause a movement of air independent of variations in temperature. For purposes of illustration I have shown four of these air moving devices, one near each 100 105 110

corner of the vehicle. Any suitable form of air moving device may be used, and as herein shown the air moving device consists of a series of vanes 11 formed into a wheel and 5 mounted in a suitable casing. When these vanes are rotated the air is drawn in through the central opening 12 and is discharged through the opening 13. Some suitable means is provided for actuating the air moving devices and I have illustrated a driving device therefor which utilizes the motion of the vehicle. This driving device consists of a wheel 14 having a series of blades 15 (see 10 Fig. 4) and is located at some suitable point 15 where the air currents produced by the moving of the vehicle can act upon it. In the construction shown each wheel 14 is mounted in a casing 16 which is open at the ends 17 and 18 so that the air passes therethrough. 20 The casings are preferably provided with the inclined shields 19 which prevent the air from striking the blades when in one position, but guide the air to the blades when in another position, as clearly illustrated in Figure 4. It will thus be seen that 25 as the vehicle moves the current of air strikes the paddles 15, rotates the wheel, and this wheel rotates the air moving devices 11. Even when the vehicle is standing still if 30 there is a current of air the wheels 14 will be rotated and the air moving devices 11 actuated.

I have described in detail a particular construction embodying my invention, but 35 it is of course evident that the parts may be varied in many particulars without departing from the spirit of my invention as embodied in the claims hereto attached, and I therefore do not limit myself to the particular construction shown.

The use and operation of my invention 40 are as follows:

When the device is in use and the temperature varying device is in operation, whether 45 it be for cooling or warming, the pipes 7 and 8 will be either heated or cooled. If now the car is in motion the wheels 14 will be rotated so as to drive the air moving devices 11. The air moving devices then move 50 the air in the car, thereby producing a circulation independent of the variations in temperature and hence a substantially uniform temperature throughout the car is maintained. The air moving devices are 55 not required to do very much work as they need simply start the air by producing a comparatively small variation in pressure, whereupon the air is moved in its effort to equalize the pressure. It will thus be seen 60 that only a small amount of force is required

to operate the wheels 14 and hence a proper circulation and a substantially uniform temperature is secured and maintained, practically without cost, by utilizing the movement of the vehicle. I prefer to locate the 65 air moving devices near the top of the vehicle and in proximity to the pipes 7 and 8, that is, to the portions of the temperature varying devices by means of which the air in the compartment is heated or cooled relatively to the outside air. The air moving device or devices, however, may be located wherever desired.

I claim:

1. A temperature regulating device for 75 moving compartments comprising an air-moving device mounted on the side wall of the compartment and communicating with said compartment but shut off from the outside air, a wheel outside of said compartment and provided with a series of blades, said wheel and said air-moving device mounted on the same shaft, a casing attached to the side of the compartment, a shield, said shield and casing associated with 80 the wheel, said shield having an inclined portion forming with said casing a converging passage and adapted to prevent the current of air from striking the blades when in one position but to direct the air against 85 the blades when in another position, the passage through the casing having a straight bottom portion located below the bottom of the wheel.

2. A temperature regulating device for 95 moving compartments comprising a temperature varying apparatus, a series of separated wheels supported on the sides of the compartment and located on the inside near the top of said compartment, said wheels 100 provided with a series of vanes, separate casings for each of said wheels having downwardly extending discharge openings, admission openings for said casings communicating with the interior of the compartment 105 only, wheels outside of the compartment, each provided with a series of vanes, said wheels being connected with the associated wheels on the inside of the compartment so as to rotate the same when the compartment 110 is moving and produce a circulation of the air about said temperature varying device.

In testimony whereof, I affix my signature in the presence of two witnesses this 16th day of December, 1918.

CHARLES W. McCOY.
